UNITED STATES PATENT OFFICE

98,395

DESIGN FOR A MILLING MACHINE STANDARD

Benjamin P. Graves, Cranston, R. I., assignor to
Brown & Sharpe Manufacturing Company, a
corporation of Rhode Island

Application July 2, 1935, Serial No. 57,492

Term of patent 14 years

To all whom it may concern:

Be it known that I, Benjamin P. Graves, a citizen of the United States of America, residing in Edgewood, city of Cranston, county of Providence, State of Rhode Island, have invented a new, original, and ornamental Design for a Milling Machine Standard, of which the following is a specification, reference being had to the accompanying drawing, forming a part thereof.

Fig. 1 is a perspective view of a milling machine standard, illustrating the same in one position;

and Fig. 2 is a perspective view illustrating the same in a different position, showing my new design.

The dominant feature of the design is directed particularly to the overhanging portion of the standard at the upper part thereof.

I claim:

The ornamental design for a milling machine standard, substantially as shown and described.

BENJAMIN P. GRAVES.
